UNITED STATES PATENT OFFICE.

GILBERT L. ADAMS, OF ELDORADO, PENNSYLVANIA, ASSIGNOR OF ONE-HALF TO
CHARLES F. BROWN, OF HOLLIDAYSBURG, PENNSYLVANIA.

TIE-PLATE.

1,392,733.

Specification of Letters Patent.

Patented Oct. 4, 1921.

Application filed December 17, 1919. Serial No. 345,458.

To all whom it may concern:

Be it known that I, GILBERT L. ADAMS, a citizen of the United States, residing at Eldorado, in the county of Blair and State of Pennsylvania, have invented certain new and useful Improvements in Tie-Plates; and I do hereby declare the following to be a full, clear, and exact description of the invention, such as will enable others skilled in the art to which it appertains to make and use the same.

This invention relates to tie plates and the primary object of the invention is to provide an improved means for locking the rails together, so as to prevent the spreading of the same in relation to each other and thereby eliminating the accidents usually occurring when the rails spread in relation to each other.

Another object of the invention is the provision of an improved tie plate and rail fastener and brace consisting of a plate extending the length of the tie for receiving the two rails and detachable grips or clips carried by the plate for engaging the rails to positively lock the rails in place and thereby prevent spreading of the same and lateral movement in relation to each other.

A further object of the invention is the provision of a tie plate having detachable grips or clips which are so formed that the same can be readily and quickly secured in position and having means to positively prevent displacement thereof.

With these and other objects in view, the invention consists in the novel construction, arrangement and formation of parts, as will be hereinafter more specifically described, claimed and illustrated in the accompanying drawing, in which—

Figure 1 is a side elevation of the improved tie plate and rail fastener showing the same attached to a tie and in operative position with the rails,

Fig. 2 is a plan view of the improved tie plate and rail fastener showing the same in operative position,

Fig. 3 is a section taken on the line 3—3 of Fig. 2,

Fig. 4 is a transverse section through a tie taken between the rails and looking toward one of them,

Fig. 5 is a detail perspective view of the rail grip or clip,

Fig. 6 is a detail perspective view of one end of a modified form of tie plate used for

straight tracks, showing the rail grips removed therefrom,

Fig. 7 is a detail side elevation of a modified form of rail grip which is adapted to be used on straight rails, and

Fig. 8 is a plan view of the rail grip used with straight rails.

Referring to the drawings in detail, wherein similar reference numerals designate corresponding parts, throughout the several views, the numeral 1 generally indicates the improved device which includes a substantially rectangular elongated flat plate 2 which is adapted to be positioned on the ordinary type of tie 3 and is adapted to receive the rails 4.

The tie plate 2 is provided adjacent to each end thereof with rail clamping ears 5, which are struck up from the body of the plate and bent forwardly as at 7 so as to engage the inner edges of the base of the rails and in placing the rails 4 in position on the plate, the bases of the same are adapted to be inserted under the clamps. An inwardly extending slot 8 is cut into the plate in one longitudinal edge thereof to a point substantially centrally of the plate and in spaced relation to the clamp 5 which slot extends parallel with and adjacent to the outer edge 85 of the rail base and is adapted to receive the locking cleat 9 formed on the lower face of the detachable rail grip or clip 10.

The rail grip 10 includes a substantially flat plate 11 having the locking cleat 9 formed on its lower face, which locking cleat extends inwardly from the side edge of the plate to a point short of the longitudinal center of the same and is adapted to be approximately the same length as the slot 8 and has formed on its forward face adjacent the lower edge thereof the outwardly projecting locking flange 12 which is adapted to engage the lower surface of the tie plate, and in operation of the same, the cleat is slid in from the open end of the slot the flange 12 engaging the under surface of the plate, and thus upward movement of the same is prevented.

The lower face of the plate 11 from the cleat 9 is beveled upwardly as at 13 so as to conform to the configuration of the base of the rails and the same is adapted to lie close up against the same. A central enlargement 14 is formed on the upper surface of the plate which projects slightly outwardly of the forward edge of the same and is pro-

vided with a plain inner surface 15 for engaging the web of the rail and an upwardly inclined surface 16 for engaging the lower surface of the head of the rail to brace the 5 same and the outer surface inclines downwardly as at 17 from the top thereof to the base. The tie 3 is recessed as at 18 for receiving the locking cleat 9, when the same is placed in position on the tie.

10 When the plate 2 has been placed in position on the tie and the rails 4 have been slipped under the clamping ears 5 and the clips 10 have been placed in position, spikes 19 are driven through the plates 11 and the 15 plates 2, which are provided with registering apertures 20 and 21 and the heads of the spikes engage the top surfaces of the plates 11 and prevent movement thereof. Spikes 22 are also provided and driven into the tie 20 1 so as to engage the outer side edges of the plates 11 of the rail grips 10 at the entrance of the slot 8 of the plate 2 and prevent accidental displacement of the locking cleats 9 therefrom.

25 From the foregoing description, it can be seen that an improved rail plate and fastener has been provided, which will absolutely lock the rails together and prevent spreading of the same.

30 The rail grips illustrated in Figs. 1 to 5 are especially adapted for use on curves, and in Figs. 7 and 8 is illustrated a rail grip which can be used on straight rails when so desired. The rail grips illustrated 35 in Figs. 7 and 8 include a substantially flat circular plate 23 having the centrally up-standing shank 24 provided with an enlarged head 25 which has its lower surface inclined toward one edge thereof as at 26.

40 The head is formed similar to a spike head and is substantially elliptical in plan. In use of the clip, the circular base 23 is placed under the plate 2 and the shank 26 is slid into the slot 8 and the head is hit with a 45 suitable instrument so as to rotate the same

and bring the head into engagement with the base of the rail 4 so as to hold the same in locked position. A spike is then driven into engagement with the plate which is provided with a peripheral notch 27 for receiving the same and the spike prevents accidental movement of the same. As clearly shown in Fig. 6 the tie plate 2 when used for straight rails is provided with a pair of slots 8 and two rail grips are used for each rail. 50

The rails are to be electrically insulated from each other by suitable means when so desired. 55

In practice, I have found that the form of my invention, illustrated in the accompanying drawings and referred to in the above description, as the preferred embodiment, is the most efficient and practical; yet realizing the conditions concurrent with the adoption of my device will necessarily vary, I 60 65 desire to emphasize the fact that various minor changes in details of construction, proportion and arrangement of parts may be resorted to, when required without sacrificing any of the advantages of my invention 70 as set forth.

What I claim as new is:

A device of the class described including a plate, a clip having a base overlapping the base flange of a rail, said plate having a slot 75 extending inwardly, a fastening member depending from the base through said slot and under the plate, a support for the tread flange of the rail rising from the base, said fastening member serving to rigidify the 80 support and base, and fastening means common to the base and plate passing therethrough opposite the support and fastening member.

In testimony whereof I affix my signature 85 in presence of two witnesses.

GILBERT L. ADAMS.
